(57) **CLAIM**

The ornamental design for a floating table, as shown and described.

DESCRIPTION

- 1.1 is a Front view of the floating table;
1.2 is a Left side view of the floating table of 1.1;
1.3 is a Top view of the floating table of 1.1;
1.4 is a Right side view of the floating table of 1.1;
1.5 is a Back view of the floating table of 1.1;
1.6 is a Perspective view of the floating table of 1.1; and
1.7 is a Bottom view of the floating table of 1.1.
The broken lines in the Reproductions illustrate portions of the article that form no part of the claimed design.

1 Claim, 7 Drawing Sheets
